SYRINGE

Roy A. Kayler, Rte. 2, Box 214, Moses Lake, Wash.
Filed Feb. 23, 1962, Ser. No. 175,163
5 Claims. (Cl. 128—218)

This invention relates to improvements in syringes and more particularly to syringes designed for the hypodermic injection of a liquid medicament into livestock such as cattle, horses, sheep and the like. Specifically stated, the present invention pertains to the provision of an improved form of hypodermic syringe to be used by cattle-men primarily for the treatment of various diseases or sicknesses of cattle.

It is one of the principal objects of this invention to provide a safe and practical syringe for the above stated purpose that does not require the usual corralling, capturing and securing the animals for the reception of injections from the syringe; which is relatively simple in its construction and mode of use and which can be easily used on an animal by a rider on horseback or while riding in an automobile or other vehicle.

It is also a principal object of the present invention to provide a syringe of the general hypodermic type; that is characterized by use of a plunger therein that may be retracted against and held under spring pressure or tension for its automatic release to effect injection of the medicament therefrom incident to the pressure applied by the user in projecting the hypodermic needle of the syringe into the animal.

Further objects and advantages of the invention reside in the details of construction of the various parts comprised in the syringe; in their combination and in the mode of use of the syringe, as will hereinafter be described.

In accomplishing the above mentioned and other objects of the invention, I have provided the improved details of construction, the preferred forms of which are illustrated in the accompanying drawings, wherein:

FIG. 1 is a side view of the present syringe, showing its parts as adjusted and held in readiness for the injection of a charge of medicament therefrom into an animal.

FIG. 2 is a similar view showing the position to which the movable parts of the syringe have been actuated by the injecting operation.

FIG. 3 is an enlarged, longitudinal section of the syringe taken in its axial line; showing the cylinder thereof as charged with a medicament and the plunger set ready for the discharge of the medicament.

FIG. 4 is a cross-section, taken on line 4—4 in FIG. 3, showing the plunger retaining latches in their plunger holding positions.

FIG. 5 is a cross-section taken on line 5—5 in FIG. 4.

FIG. 6 is a cross-section on line 6—6 in FIG. 3 showing the outer or closed inner end of the syringe.

FIG. 7 is a view showing the outer or needle carrying end elevation of the syringe as seen in FIG. 3.

FIG. 8 is a view showing the manner of mounting the syringe on an elongated handle member for its more convenient use by a rider.

Referring more in detail to the drawings:

The present syringe is designated in its entirety in FIGS. 1, 2 and 3 by reference numeral 10 wherein it is shown to comprise a tubular or barrel-like body portion 11; an outer end portion 12 hereinafter referred to as the "tip" and an inner end "cap" portion 13. The cap portion is made up of two concentric, disk-like portions 13a and 13b later to be described in detail.

The barrel-like body 11 is a single, plastic piece of cylindrical form, that is axially bored from its inner to near its outer end, thus to provide an elongated cylindrical chamber 15 that terminates short of the outer end

2

of the body in a closure endwall 16 that has a central bore therethrough, as at 17, and this bore has a needle mounting tip 18 threaded thereinto. This tip is axially bored to provide a discharge passage 19 therethrough and its outer end is tapered to provide a mounting tip 18x over which the hub 20h of a hypodermic needle 20 suitable for this syringe may be applied for use.

The tip portion 12 of the syringe is tubular or cylindrical and of the same outside diameter as the barrel 11 and it is shown to have its outer end portion conically tapered but not necessarily so.

The inner end cap 13, of the barrel 11, as made up by the two disks 13a and 13b which are of the same diameter as the barrel, is secured firmly in place over the open inner end of the barrel by four screws 22, best shown in FIG. 6 to be equally angularly spaced and as illustrated in FIG. 5 are applied through both disks and threaded at their inner ends into the end portion of the barrel and drawn tight.

The tip end portion 12 is mounted by two elongated rods 25 that extend slidably through holes 26 bored through the cap 13; thence through bores 27 formed in diametrically opposite sidewall portions of the barrel, throughout its entire length and are then threaded into the end surface of the tip, as seen at 28 in FIG. 3. When the tip 12 is pressed firmly against the closed outer end surface of barrel or body 11, the other ends of these two rods 25 will each project approximately $\frac{1}{16}$ of an inch beyond the inner end surface of cap 13 as shown in FIG. 2. When the tip is pulled outwardly and away from the barrel, the heads of the rods 25 are engaged against the cap as in FIG. 3.

It is also well shown in FIG. 3 that a plunger 30 of lesser diameter than the cylindrical chamber 15 and formed with a piston-like inner end portion 30x is reciprocally contained in the bore 15, with the outer end portion of the plunger stem extended slidably through bores 32 and 33 formed centrally through the disks 13a and 13b to receive it. The piston-like inner end portion 30x of the plunger is equipped with a suitable sealing gasket, as at 35, and a coil spring 36 is applied about the plunger to bear at its inner and outer ends, respectively, against the piston-like portion 30x and end plate 13a to urge the plunger inwardly.

To charge the barrel chamber 15 with a medicament, the needle 20, after being properly applied to the mounting tip 18x is inserted in the liquid medicament and is caused to be sucked into the barrel by drawing the plunger outwardly to its limit. When the plunger has been pulled outwardly to a predetermined extent, it will be latched and held in readiness for use by the present latching means. The plunger latching means and its method of release will now be described.

It is to be observed by reference to FIGS. 4 and 5, that the outer surface of disk 13a is slightly recessed. Disposed flatly against the bottom surface of the recess, at opposite sides of the plunger containing bore therein are paired latch dogs 40—40, each of which is pivotally mounted between its ends by a pivot pin 41 that is fixed in the disk. The plunger stem 30 is shown in FIG. 3 to be formed at a predetermined distance from the piston end portion 30x thereof with a shallow encircling groove 42. When the plunger 30 is pulled outwardly to position of FIG. 3 to effect the sucking in of the charge of medicament, and the coil spring 36 is thereby placed under compression, it will be held in that cocked or latched position by the two latch dogs 40—40 which are caused to have end portions thereof seated, as in FIG. 4, within the encircling channel 42 of the plunger; the inward urging of the dogs for latching is effected by the use of V-shaped spring means 45—45 that are disposed in the recessed portion of the disk 13a in fixed positions and in such

manner as to exert latching pressure against the outer edges of the latching ends thereof.

To prepare the syringe for use, the tip portion 12 is first pulled outwardly and away from the closed end of the barrel, as in FIG. 1. In doing this the heads 25h of the two tip mounting and holding rods 25 are caused to be seated against the cap 13 as they have been shown in FIG. 1. Each of the rods 25 is formed lengthwise thereof along that portion adjacent its head 25h, with a sloping camming surface 59, as well shown in FIG. 5. When the two rods 25 are moved outwardly by manually pulling the tip 12 to its outer position as shown in FIG. 1, the camming surfaces of the rods recede sufficiently under spring pressure to permit the subsequent latching of the dogs in the plunger channel 42. For the injection of the medicament into the animal, the needle point is forced into the animal in such manner and to such extent as to simultaneously press the tip 12 back against the end of the barrel, and in doing this the two rods 25 which mount the tip are actuated outwardly, thus causing their sloping camming surfaces 59 to so act against the dogs as to unseat their latched ends from the plunger channel 42 to allow the coil spring to force the plunger and piston inwardly and effect the discharging of the medicament from the chamber 15 and through the needle into the animal.

It is the experience of persons who have used the present syringe for treatment of sick or diseased cattle, that it is most satisfactory and convenient for a rider on horseback or in a buggy or automobile, to ride into a herd alongside the animal and to use it for injection of medication, either while tightly grasping the syringe barrel in the hand, or by attaching a rod or pole 60 of suitable length to the barrel as in FIG. 8. Such a pole could be of any suitable length and attached at one end to the outer side of the syringe barrel 10 in any suitable manner, as for example, by use of an ordinary hose clamp 61 or the like as indicated. Also, it is apparent that the plunger powering spring 36 might be placed at the outside of the barrel 11 instead of inside it as herein shown and secured thereto at one end and to the outer portion of the plunger stem at its other end in such manner as to be placed under tension with the charging of the syringe.

Materials used in the making of the various parts of the device would be selected to best serve the purpose, without change in the use of the syringe and without endangering the medicament or the article. For instance, the barrel might be made of plastic, stainless steel, glass or other suitable materials. Likewise, the size of the device and proportional dimensions of its parts might be changed to suit conditions of use without departing from the spirit of the invention.

What I claim as new is:

1. A syringe for injecting a medicant into a body com-

prising a barrel having a piston chamber therein adapted to be filled with said medicant and having outer and inner ends adjacent to the ends of said chamber, a hypodermic needle rigidly connected to said outer end, said needle projecting outwardly from said barrel and being in communication with said piston chamber, a piston slidably and sealingly fitted within said chamber for reciprocating movement within said chamber, a ported disc secured over the inner end of said barrel, an extension connected to said piston and projecting through and rearwardly of said ported disc, a spring means connected between said piston and barrel so as to urge said piston toward said needle for forcing the medicant in said chamber through said needle, said extension having a peripheral groove formed therein, a latch pivotally mounted to said disc, resilient means urging a portion of said latch towards said extension whereby said portion may extend into said groove for retaining said piston in a position to hold said spring means compressed, an annular tip surrounding said needle and spaced between the outer end of said needle and said outer end of said barrel when said latch portion extends into said groove, support means movably connecting said tip to said barrel so that said tip may move toward and away from said outer end of said barrel, latch operating means connected to said support means and adapted to move said portion of said latch out of said groove when said tip contacts said body and is forced towards said barrel whereby said spring means may move said piston to force said medicant through said needle.

2. A syringe as defined in claim 1 wherein said support means comprises an elongated rod slidably mounted in a bore through said barrel, one end of said rod secured to said tip, said latch operating means comprising a cam surface on the other end of said rod adapted to engage said latch and force said latch portion out of said groove when said rod and cam surface are moved inwardly by said tip.

3. A syringe as defined in claim 1 including an elongated handle means connected to said barrel whereby said syringe may be moved by said handle means for forcing said hypodermic needle into said body.
